FISHING ROD HOLDER

Reaves F. Morris, 204 Bryd St.,
Oklahoma City, Okla. 73110

Filed May 28, 1970, Ser. No. 23,187

Term of patent 14 years

Int. Cl. D22—08

U.S. Cl. D22—22

FIG. 1 is a perspective view of a fishing rod holder constructed in accordance with the present invention.

FIG. 2 is an elevational view of one side of the fishing rod holder of FIG. 1.

FIG. 3 is an elevational view of one end of the fishing rod holder of FIG. 1.

FIG. 4 is an elevational view of the opposite side of the fishing rod holder from that shown in FIG. 2.

FIG. 5 is a top view of the fishing rod holder of FIG. 1.
I claim:

The ornamental design for a fishing rod holder, substantially as shown.
